UNITED STATES PATENT OFFICE.

MAXWELL R. LOECHEL, OF PHILADELPHIA, PENNSYLVANIA.

PUTTYLESS SKYLIGHT.

1,127,905.

Specification of Letters Patent.

Patented Feb. 9, 1915.

Application filed June 2, 1914. Serial No. 842,490.

To all whom it may concern:

Be it known that I, MAXWELL R. LOECHEL, a citizen of the United States, residing at Philadelphia, in the county of Philadelphia and State of Pennsylvania, have invented 5 certain new and useful Improvements in Puttyless Skylights, of which the following is a specification.

My invention relates to improvements in 10 puttyless skylights, the object of the invention being to provide improved means for supporting the panes of glass, rendering them entirely water tight without the use of putty or similar material, and provide 15 means for carrying off the water as a result of condensation against the surface of the glass.

A further object is to provide improved 20 means for holding the panes of glass, said means operating to give an elastic support, cushioning the panes of glass and permitting expansion and contraction without any danger of breakage or leakage.

With these and other objects in view, the 25 invention consists in certain novel features of construction and combinations and arrangements of parts as will be more fully hereinafter described and pointed out in the claims.

30 In the accompanying drawings: Figure 1 is a diagrammatic plan view showing an ordinary straight skylight. Fig. 2 is a broken view in longitudinal section on an enlarged scale on the line 2—2 of Fig. 1.

35 Fig. 3 is a view in cross section on an enlarged scale on the line 3—3 of Fig. 1. Fig. 4 is a similar view on the line 4—4 of Fig. 1. Fig. 5 is a view in longitudinal section on an enlarged scale illustrating a 40 lap joint. Fig. 6 is a view similar to Fig. 4 illustrating a modification. Figs. 7 and 8 are views in plan and elevators more or less diagrammatic illustrating a hip skylight embodying my improvements, and on Fig.

45 7 I indicate section lines 3—3 and 4—4 which are precisely the same as the sections above referred to in connection with Fig. 1. Fig. 9 is a view in section on an enlarged scale on the line 9—9 of Fig. 7, and Fig. 10 50 is a view similar to Figs. 4 and 6 illustrating another modification.

1 represents the outside walls or curbs of the skylight which are capped by angle bars 2 and covering plates 3, and anchoring clips 4 are provided to secure the skylight on the curb or wall. My invention is not limited

5 to this detail of construction. I have not attempted to illustrate any particular number of such anchor clips, but I would have it understood that I might use as many 60 as desired and clamp them by bolts 5 which can be removed if desired.

The end angle bars 2 are connected by 65 longitudinal vertically disposed bars 6, which to distinguish them from other bars, I shall hereinafter refer to them as "filler bars." These bars 6, at their ends, are secured to the angle bars 2 in any approved manner, and are provided at intervals with 70 cross pins 7.

On the bars 6 and extending throughout 75 their length, glass supporting bars 9 are secured by rivets 10. The pins 7 support and limit the downward movement of the supporting bars 9. These bars 9 are formed 80 from relatively thin metal plates, preferably of copper, bent intermediate their edges forming a longitudinal inverted U-shaped portion as shown at 11 fitting over the bar 6 and having its parallel members rigidly 85 secured to the bars by means of the rivets above referred to.

The edges of the plate forming the bar, after extending downwardly at both sides of the bar 6, curve outwardly in opposite 85 directions forming condensation gutters 12 supported on the pin 7. The plate, at its edges, is then bent inwardly forming other condensation gutters 13, and is then bent 90 upwardly and downwardly forming hooks 90 supporting cushions 14, the panes of glass being indicated by the reference numeral 15.

At intervals, throughout the length of the bar 6, I provide springs 16. These springs 95 are preferably of brass, approximately narrow, and straddle the bars 6 and 9. They are formed of strips of spring metal with their intermediate portion perforated as shown at 17, so that the vertically screw-threaded portions 18 of T-bolts 19 may project there-through. The horizontal portions of these T-bolts are held against the upper edges of the bar 9 in any approved manner. As a simple means of connecting the parts, I have provided openings 20 in the sides of the 100 springs 16 and filled said openings with solder as shown at 21, the solder operating to rigidly hold the parts together.

The lower portion of the spring, at both 115 sides, is bowed outward as shown at 22 constituting cushioning surfaces against which the edges of the panes of glass 15 may bear.

This arrangement of spring cushion for the edge of the glass allows the latter to expand and contract without danger of breaking and without causing any leakage.

5 The lower ends of the spring are curved outwardly as shown at 23, and confined under the cushioning portions 14 of the bar 9. Spring cap bars 24 are located above the bars 6 and 9 and have their edges curved 10 outwardly and then inwardly forming 15 spring contact points 25, engaging the upper faces of the panes of glass.

The intermediate portion of the cap bars is of general inverted U-shape and provided 15 with openings 26 to receive the vertical portions 18 of the T-bolts 19, and dome nuts 27 are screwed onto the T-bolts against the cap bar and permit the cap bar to be forced 20 downwardly against the glass to hold the same as tightly as desired. It will thus be noted that the panes of glass 15 are supported upon cushions 14, and that their edges when the panes of glass expand, will engage cushions 22, so that the glass is supported 25 both vertically and horizontally by means of spring cushions. This insures a tight joint regardless of expansion and contraction. Furthermore, the cushions 14 operate as baffles to stop the water which 30 condenses on the bottom of the glass, and compel it to enter the gutters 13. Any water which passes this point or which finds its way into the joint at other places, will enter the gutters 12 and will be directed down the 35 skylight into a gutter 28 extending transversely across the skylight and supported in a bar 29 which is preferably of the general stepped form indicated.

Where the skylight is made up of several 40 longitudinal sections of glass, it is necessary to provide a joint which will properly connect them. In Fig. 2, I indicate a butt joint in which a transverse sheet 30, preferably of lead, is interposed between the panes of glass 45 with its intermediate portion corrugated as shown at 31 to allow for expansion and contraction, and its inner portion bent forming a condensation gutter 32. As a modification of this feature, I indicate in Fig. 5, a 50 lap joint in which a sheet 32^a is interposed between the overlapping panes of glass, and provided with a condensation gutter 33, below the uppermost pane of glass.

The skylight at the outside walls or curbs 55 is provided with filler bars 34 which support bars 35. These bars 35, on their inner edges, are formed precisely like one half of the bar 9 above referred to, that is to say, it is provided with condensation gutters 12 and 13 60 and with a cushion 14 to support the glass 15. The outer portion of the bar, however, lies flat against the filler bar 34 except at a point adjacent the upper edge of the bar, where it is off-set as shown at 36, and the 65 lower edge is bent around the curb as shown

at 37 to render the construction water tight. A spring 38, corresponding to spring 11, is formed at its inner side precisely like the spring 11, that is to say, it is provided with a spring cushion 22 to receive the edge of the 70 pane of glass, and its lower end 23 engages under the cushion portion of the bar 35. Spring bar 38 confines T-bolts 39, corresponding to T-bolts 17, and dome nuts 27 are employed to secure cap bars 40 in position. 75

The bars 40 bear against the glass 15, and at their outer edges are curved as shown at 80 41 to project over the off-set portion 36 and shed the water that falls thereon.

At the upper end of the skylight, the glass 15 is supported between the cap bar 42 and a cushioning bar 43, both secured to a bar 44 on the outside of the angle bar 2 as shown.

In the modification illustrated in Fig. 6, 85 the parts are precisely like the construction indicated in Fig. 4 with the exception that the bar 45, corresponding to bar 9, is somewhat differently bent at its lower ends to provide cushions 46 and gutters 47 corresponding to the cushions 14 and gutters 13 of the preferred form. The gutters 47 are formed by bending the edges of the bar or plate in the arc of a circle inwardly, and the cushion portion 46 is formed by giving 90 the edges of the plate or bar a convex curve inwardly. This is also true of the modification shown in Fig. 10, in which the bar 48 corresponding to the bar 9 is curved outwardly and then inwardly in the arc of a 95 circle to form condensation gutters 49, corresponding to the gutters 12, and is then curved outwardly in a general compound curve to form cushions 50 and condensation 100 gutters 51 corresponding to the cushions 105 14 and gutters 13.

When my improvements are in use in connection with a hip skylight such as shown in Figs. 7 and 8, the ridge bar is formed by a filler bar 52 having supporting bars 53 secured thereto and supporting on cushions 54, the panes of glass 15. 110

A cap bar 55 is secured in any approved manner, and bears against the upper face of the panes of glass. The supporting bars 53 are interlocked at their upper edges as shown at 56, and between their upper and lower edges are provided with laterally offset portions 57 to bear against the filler bar 52 and prevent any collapse of the ridge. The lower edges of the bars 53 are curved 120 upwardly to form the cushions 54, and also form condensation gutters 58, so that any moisture condensing inside of the ridge will be carried off by these gutters. 125

With all forms of my improvements, it will be noted that the panes of glass are supported upon spring cushions, are pressed downwardly upon the cushions by spring cap bars, are permitted longitudinal expand- 130

sion and contraction by reason of spring cushions, and condensation gutters are provided so that all moisture forming on the under surface of the glass, will be carried to 5 a common gutter or outlet and escape.

It will also be noted that the panes of 10 glass are supported and rendered water tight without the employment of putty or any similar material, and that the glass may be clamped as tightly as desired to provide a water tight joint.

Various slight changes might be made in 15 the general form and arrangement of parts described without departing from my invention, and hence I do not limit myself to the precise details set forth, but consider myself at liberty to make such changes and alterations as fairly fall within the spirit and scope of the appended claims.

Having thus described my invention, what 20 I claim as new and desire to secure by Letters Patent is:

1. The combination with a filler bar, a 25 glass supporting bar secured on the filler bar and having at its lower edge a laterally projecting portion constituting a condensation gutter and a cushion, a pane of glass on said cushion, springs secured over the supporting bar and having a cushion in line with

the edge of the pane of glass, the free ends 30 of said springs inclosed within the laterally projecting portion of the supporting bar, and a cap bar covering the springs bearing upon the pane of glass, substantially as described.

2. The combination with a filler bar, a 35 glass supporting bar secured on the filler bar and having at its lower edges laterally projecting portions constituting condensation gutters and cushions, panes of glass on 40 said cushions, springs secured over the supporting bar and having cushions in line with the edges of the panes of glass, the free ends of said springs inclosed within the laterally projecting portions of the supporting bar, 45 T-bolts secured by the springs on top of the filler bar and projecting upwardly, a cap bar having openings therein through which the bolts project, and nuts located on the ends of the bolts bearing against the cap 50 bar, substantially as described.

In testimony whereof I have signed my name to this specification in the presence of two subscribing witnesses.

MAXWELL R. LOECHEL.
